INVENTOR:

Allan H. Hascall,

BY

Braentzel and Richards,
ATTORNEYS

UNITED STATES PATENT OFFICE.

ALLAN H. HASCALL, OF NEWARK, NEW JERSEY.

LIFTING JACK FOR THE SIDE CARS OF MOTOR CYCLES.

Application filed February 21, 1920. Serial No. 360,366.

To all whom it may concern:

Be it known that I, ALLAN H. HASCALL, a citizen of the United States, residing at Newark, in the county of Essex and State 5 of New Jersey, have invented certain new and useful Improvements in Lifting Jacks for the Side Cars of Motor Cycles; and I do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

This invention relates, generally, to improvements in lifting jacks for vehicles; and, the present invention has reference, more particularly, to a novel jack for use 20 in connection with the side-car of a motor-cycle, with a view of directly connecting the jack with the axle of the side car for raising its wheel when it is desired to remove or replace a tire.

The present invention, therefore, has for 25 its principal object to provide a novel and simply constructed, as well as an efficiently operating jack for the side-car of a motor-cycle, the jack being permanently carried by 30 the axle of the side-car, by being pivotally connected with the axle, the jack being adapted to be lowered so as to be brought into a substantially vertical supporting relation with the road-surface when the wheel 35 is to be raised, and the axle being provided with a clamping means with which the jack can be swung into holding engagement when not desired, and so as not to interfere 40 with the use of the motor-cycle and its side-car.

Other objects of the present invention not at this time more particularly enumerated will be clearly understood from the following detailed description of the present invention. 45

With the various objects of the present invention in view, the said invention consists, primarily, in the novel lifting jack for the side-car of a motor-cycle hereinafter 50 more fully set forth; and, the said invention consists, furthermore, in the novel arrangements and combination of the several devices and parts, described more in detail in the following specification, and then 55 finally embodied in the clauses of the claims

which are appended to and which form an essential part of the said specification.

The invention is clearly illustrated in the accompanying drawings, in which:—

Figure 1 is a rear-end view of one type 60 of motor-cycle and side-car, showing in connection with the axle of the side-car and its wheel, a jack pivotally connected with the axle, said jack being swung in its parallel relation with the axle and in holding 65 engagement with a clamping means with which the axle is provided.

Figure 2 is a similar view of the motor-cycle and side-car, with the jack shown in its disengaged relation with the clamping 70 means, and in supported relation with the road-surface, for raising the wheel of the side-car from the road-surface for the purpose of removing or replacing a tire.

Figure 3 is a transverse vertical sectional 75 representation taken on line 3—3 in said Figure 1, looking in the direction of the arrow X; and Figure 4 is a similar section, taken on line 4—4 in said Figure 1, also looking in the direction of the arrow X, 80 both of said views being made on an enlarged scale.

Similar characters of reference are employed in all of the said above described views, to indicate corresponding parts. 85

Referring now to the said drawings, the reference-character 1 indicates, in a general manner, a motor-cycle of any known construction, and 2 indicates the usual side-car thereof. The reference-character 3 indicates the usual axle of the side-car, 4 the wheel at one end of the said axle, and 5 denotes any usual and well-known mechanism for oscillatorily connecting the other end of the axle 3 to the frame-work of the 90 motor-cycle. Suitably mounted upon said axle 3, near the wheel 4, is a sleeve-like member or collar 6 which is provided with a pair of downwardly extending members 7 carrying near their lower end-portions, a 95 pintle 8. Pivotedly mounted upon the said pintle 8 and between the said downwardly extending members 7 of the collar 6 is the reduced and perforated end-portion 10 of a suitably-formed rod or post 9, these several 100 parts providing the jack, as will be clearly understood from an inspection of Figures 1 and 2 of the drawings.

Suitably connected with the said axle 3 and located in the proper position thereon 110

with relation to the sleeve-like member or collar 6 is a clamping means with which the said rod or post 9 can be brought into detachable holding engagement, in the manner illustrated in said Figures 1 and 4 of the drawings.

One form of such clamping device as here shown consists, essentially, of a pair of members 11 and 12 having perforated ears 10 or lugs 13 and 14, at their opposite edges, said ears being in registration with each other, and being connected by a pin 15 upon which is suitably mounted the usual coil-spring 16.

Extending from the respective members 11 and 12 are the usual convexly shaped clamping or holding elements 17 and 18, which as shown are adapted to embrace the axle 3 and are securely held in their embracing relation with the axle by the action of the said coiled spring 16 and its respective ends against the inner faces of the peculiarly shaped rod or post-receiving elements 19 and 20 which are also connected 25 with the members 11 and 12, and extend in downward directions from said members, as clearly shown in Figures 1, 2 and 4 of the drawings.

Having in the foregoing set forth the general arrangements and constructions of the several devices, any further description of their operations for raising the wheel of the side-car, as shown in Figure 2 of the drawings, or swinging the jack into its retained engagement with the clamping device mounted upon the axle 3 are deemed unnecessary, as all of this will be clearly understood from an inspection of said figures of the drawings.

I am aware, however, that some changes may be made in the general arrangements and combinations of the several devices and parts, as well as in the details of the construction of the said parts, without departing from the scope of the present invention.

tion as set forth in the foregoing specification, and as defined in the clauses of the claims which are appended thereto. Hence, I do not limit myself to the exact arrangements and combinations of the several devices, and parts as described in the said specification, nor do I confine myself to the exact details of the construction of the said parts as illustrated in the accompanying drawings.

I claim:

1. In a side-car for motor-cycles, an axle and its wheels; a sleeve-like member mounted upon said axle, perforated lugs extending from said member, a pintle carried by said lugs, a jack-rod pivotally connected with said pintle, and means consisting of a pair of pivotally connected and spring-controlled members, said members being formed at one end with convexly shaped axle-embracing elements for mounting said means in a fixed position upon said axle, and said members being formed at their opposite ends with rod-receiving and clamping elements with which said jack-rod is adapted to be brought into detachable holding engagement.

2. In a side-car for a motor-cycle, an axle and its wheels, a sleeve-like member mounted upon said axle, perforated lugs extending from said member, a pintle carried by said lugs, a jack-rod pivotally connected with said pintle, and a clamping device mounted upon said axle and comprising a pair of spring-controlled clamping members between which said jack-rod is adapted to be brought into detachable holding engagement.

In testimony that I claim the invention set forth above I have hereunto set my hand this 20th day of February, 1920.

ALLAN H. HASCALL.
